REINFORCING INSERT FOR ANTIDRIP ATTACHMENT FOR PAINT BRUSHES

John F. Kunau, Long Beach, Calif.

Application January 6, 1949, Serial No. 69,566

1 Claim. (Cl. 15—248)

1

The present invention relates to the category of inventions classified as attachments for paint brush heads and referred to as drip collecting cups, collars, guards and the like and the object of the invention is to structurally, functionally and otherwise improve upon those attachments with which I am familiar.

With further reference to the prior art it may be stated that the generally accepted type of drip collector embodies a trough or channel which in practice serves to trap paint such as runs down the various surfaces of the head while painting a ceiling or similar overhead surface. The majority of drip collectors are rigid and are made to fit a given size of a brush. Some drip collectors however have been made of rubber to snugly embrace the brush head and to thereby serve to accommodate brush heads of varying sizes. The difficulty, however, is that if a rubber type trough equipped collar is overstretched, the walls forming the trough will collapse and become ineffective.

It follows from the above that the present invention has to do with an improved reinforcing insert for an elastic or resilient collar having a trough of the stated type, said collar being improved by having incorporated in the transverse end portions reinforcing inserts, the latter making the collar more practical and yet allowing same to be fitted on brush heads of differing sizes.

More explicitly, the invention has to do with a metal or equivalent insert used as a reinforcing unit, the same characterized by a U-shaped sheet metal clip and suitable reinforcing rod members carried by one limb of the clip.

Other objects and advantages will become more readily apparent from the following description and the accompanying illustrative drawings.

In the drawings:

Figure 1 is a perspective view of a conventional-type paint brush equipped with an anti-drip attachment collar constructed in accordance with the principles of the present invention;

Figure 2 is a perspective view of the reinforcing insert;

Figure 3 is a horizontal section on the line 3—3 of Figure 1, looking in the direction of the arrows; and,

Figure 4 is a fragmentary cross section on the line 4—4 of Figure 3.

Referring now to the drawings by distinguishing reference numerals the wooden or equivalent head of the brush is denoted by the letter A the same having a suitable handle B. The usual metal shield around the head is denoted at C and the bristles at D.

The rubber or equivalent anti-drip attachment is denoted, in a unitary sense, by the numeral 6. It is in the form of a channel-shaped collar which is shaped and made to fit around a head or shield

of the brush. When in place the collar or attachment defines a pair of longitudinal or side channels 7 and 8 and a pair of transverse or end channels 9 and 10 which in practice serve as drip collecting channels or troughs. The inner wall of the collar is suitably tapered and relatively thin and denoted by the numeral 11 and the outer wall is comparatively thick and denoted by the numeral 12.

10 I provide reinforcing inserts for opposite transverse end portions of the collar and each insert is of the construction shown in Figure 2. Here the insert comprises a metal or equivalent U-shaped clip 13 having a bight portion 14 and inner and outer limbs 16 and 15 respectively. The inner limb 16 is somewhat longer than the outer limb 15 and is centrally imbedded in the inner thinner wall 11 as shown to advantage in Figure 4. The outer limb is appropriately imbedded 15 in the outer thicker wall 12 as shown in Figure 4. The outer limb is also provided with substantially U-shaped reinforcing rods. The main or body portions 17 of the rods being imbedded in the wall 12, the end portions extending around the 20 corners of the adjacent channels and being imbedded in the corresponding end portions of the side walls 12, said laterally bent ends being denoted by the numerals 18.

These reinforcing inserts substantially span and 25 brace the transverse ends only of the head encircling collar. There is sufficient elasticity and resiliency in the collar to make it adjustable. By keeping the transverse ends of the channel at all times open, the side channels are also maintained 30 spread and open. In other devices the channel or trough is often collapsed and therefore closed. In the present improved arrangement the channels are completely open for effective drip trapping 35 results.

40 I desire to stress the fact that the cross or transverse channels 9 and 10 are braced from end to end and the adjacent end portions of the respective and intervening longer channels 7 and 8 are also braced due to the provision of the laterally bent ends 18 of the reinforcing rods. It 45 follows that all of the features contribute their proportionate shares in providing an adequately and satisfactorily usable paint brush anti-drip attachment.

50 It is thought that persons skilled in the art to which the invention relates will be able to obtain a clear understanding of the invention after considering the description in connection with the drawings. Therefore, a more lengthy description 55 is regarded as unnecessary.

Minor changes in the shape, size and arrangement of details coming within the field of invention claimed may be resorted to in actual practice, if desired.

Having described the invention, what is claimed as new is:

As a new article of manufacture and as a component part of a paint brush anti-drip attachment of the class described, a U-shaped clip embodying long and short limbs, and a pair of U-shaped rigid reinforcing rods, the respective intermediate portions of said rods being rigidly connected with the short limb of said clip and the free lateral ends of said rods being directed from said short limb and toward said long limb. 10

JOHN F. KUNAU.
